US0D1111770S

(12) **United States Design Patent** (10) **Patent No.:** **US D1,111,770 S**
(45) **Date of Patent:** **** Feb. 10, 2026**

(54) **COMPONENT FOR A LOCK**

(71) Applicant: **Guangzhou Sair Industrial Co., Ltd,**
Guangzhou (CN)

(72) Inventor: **Jiye Guo**, Guangzhou (CN)

(73) Assignee: **Guangzhou Sair Industrial Co., Ltd,**
Guangzhou (CN)

(**) Term: **15 Years**

(21) Appl. No.: **29/958,900**

(22) Filed: **Aug. 22, 2024**

(30) **Foreign Application Priority Data**

May 14, 2024 (CN) 202430283544.8

(57) **CLAIM**

The ornamental design for a component for a lock, as shown and described.

DESCRIPTION

FIG. 1 is a front, right and top perspective view of a component for a lock, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the component for a lock that form no part of the claimed design.

1 Claim, 8 Drawing Sheets
